BINDER DETACHABLE HAND REST

Filed June 24, 1949

UNITED STATES PATENT OFFICE

2,579,915

BINDER DETACHABLE HAND REST

Glenn M. Flatin and Alvin H. Rorvig,
Rothsay, Minn.

Application June 24, 1949, Serial No. 101,188

1 Claim. (Cl. 281—16)

1

This invention relates to an extension hand rest for book binders and the like.

It is an object of this invention to provide an extension hand rest, of the kind to be more particularly described hereafter, having means for detachably securing the hand rest to an outer cover of a loose-leaf book binder and the like and having hinged hand rest leaves hingedly supported between the outer covers of the hand rest.

Another object of this invention is to provide a hand rest of this kind which may be readily made in different sizes to fit various sizes of books, binders, and the like.

Still another object of this invention is to provide a hand rest of this kind to make writing in books as ledgers and the like, easier when reaching the bottom of the pages.

With the above and other objects in view, our invention consists in the novel combination arrangement and details of structure set forth in the specification and drawings, and then more particularly described in the appended claim.

In the drawings:

Figure 1 is a perspective view of a book binder constructed according to an embodiment of our invention.

Figure 2 is an end elevation thereof.

Figure 3 is a top plan view, partly broken away, of a detachable hand rest secured on a loose-leaf book binder.

Figure 4 is a fragmentary detail section taken on the line 4—4 of Figure 2.

Figure 5 is a top plan view of one of the clamping elements, removed from the assembly.

Figure 6 is a fragmentary longitudinal section taken on the line 6—6 of Figure 5.

Figure 7 is a fragmentary longitudinal section taken on the line 7—7, of the lower end of the clamping element.

Figure 8 is a transverse section taken on the line 8—8 of Figure 6.

Referring to the drawings, the numeral 10 designates generally a loose-leaf book binder, of substantially conventional construction used for a ledger or for supporting paper leaves 11 for writing. The loose-leaf binder 10 is formed of a pair of hinged outer cover members 12 and 14 hingedly connected together by a hinged connection on a center cover member 15. The loose-leaf binder 10 is formed with split rings 16 mounted on a resilient ring supporting member 17, which in turn is fixedly secured to the center cover member 15 by rivets 18 or other suitable fastening devices.

In the use of loose-leaf book binders of this

2

substantially conventional type the leaves 11, supported for writing, have the side edges thereof extending outwardly to the side edges of the cover members 12 and 14. It is intended, in the use of the binder detachable hand rest 19 constructed according to an embodiment of this invention, to have the side edges of the leaves 11 terminated inwardly from the extreme outer side edges of the cover element 12 and 14, as clearly shown in Figures 1 and 3 of the drawings. By disposing the outer side edges of the writing sheets 11 inwardly from the outer edges of the cover members sufficient space is provided, in the open portion of the book binder 10, for engaging a pair of clamping elements 20 and 21 on the side edges of the binder cover without interfering with the turning or folding of the pages 11, while providing for the suitable fixed attachment of the binder hand rest 19.

20 The binder hand rest 19 is formed of a pair of outer rigid rest cover members 22 and 24 hingedly connected together by their hinged connection to a center hand rest cover member 25. The cover members 22, 24, and 25 are formed of paper, plastic, or other suitable material substantially the same as the material from which the outer binder cover members 12 and 14 are formed. A suitable metal clamping member 26 is fixed on the inner surface of the center cover member 25 and is formed with a pair of spaced apart split rings 27 and 28 swingably mounted thereon. The rings 27 and 28 are formed in substantially the same manner as the rings 16, described above, for releasably securing a plurality of binder leaves 29 between the cover members 22 and 24. The binder leaves 29 are formed of thin sheets of paper, or other suitable material having the same thickness as the paper leaves 11 on the binder 10.

30 The binder hand rest 19 is formed for disposition on the lower edge of the binder cover in substantial planar alignment with the respective cover members 12 and 14. Each of the binder cover members 22 and 24 is formed with a pair of lugs 30 extending upwardly beyond the upper edge thereof and secured to the inner faces. The lugs 30 are adapted to be engaged on the inner surface of the respective cover members 12 and 14 when the hand rest members 22 and 24 are supported thereon. The leaves 29 on the rest 19 will be foldable about the same axis as the leaves 11.

35 Each of the clamping members 20 and 21 is formed in substantially the same manner so that a detailed description of one may be suitably applied as a description of the other.

The clamping member 20 is formed with an elongated tubular body 31 open at the upper end thereof and formed with an upwardly directed hook 32 at the lower end. The cross section of the clamping member 31 is oval in configuration and a pair of detents 34 are struck indirectly on the side edges of the upper end. The detents 34 are disposed in transverse alignment for engagement in a selected pair of detents 35 along the length of the upper telescopic clamping member 36.

The upper clamping member 36 is formed as an elongated tubular body also oval in configuration having a downwardly directed hook 37 at the upper end thereof. A plurality of outwardly opening detents 35 are struck on the side edges of the body 36 and the body 36 is slideably engaged through the upper open end of the lower clamping member 31. A set screw 38 is threadably engaged through the bight portion of the hook 37 for engagement with one edge of the outer cover members for adjustably securing the clamping element 20 on the binder cover.

In the use and operation of the binder detachable hand rest 19 the cover members 22 and 24 are disposed in alignment with the covers 12 and 14 of the binder at the lower end thereof. The clamping members 20 and 21 are engaged on the side edges of the covers on the binder 10 and rest 19. The clamping members 36 will initially be adjusted in the clamping members 31 by the telescopic engagement of the clamping member 36 in the upper open end of the clamping member 31. The set screw 38 will be adjusted for securely clamping the clamping members 21 and 22 in place with the binder rest covers 22 and 24 extending downwardly below the lower edge of the binder covers 12 and 14. The binder leaves 29 will be disposed in planar alignment with the leaves 11, so that when the leaves 11 are turned in the binder 10 the leaves 29 may be

5 turned in the rest 19 to provide a substantially level assembly.

The binder hand rest 19, thus formed, may be suitably attached to any binder for a book by the clamping members 20 and 21 and the leaves 29 may be folded or hinged with the writing leaves 11 so that a level writing surface will always be provided for writing on the lower end of each of the pages or leaves 11.

We claim:

A binder hand rest comprising a pair of substantially rigid rest members hingedly connected together for abutting disposition with one end of the hingedly connected covers of a book binder, and in planar alignment therewith, a pair of telescoping clamping members releasably engaging the opposing end of the respective covers and the rest members, connecting tabs fixed on each of said rest members for overlying the adjacent edge of the respective covers, and rest leaves hinged between said rest members for selective disposition in alignment with the leaves of the binder.
